INVENTOR

John Jacob Kinzer.
By J. M. Cooley
Attorney.

UNITED STATES PATENT OFFICE.

JOHN JACOB KINZER, OF WILDWOOD, PENNSYLVANIA, ASSIGNOR TO PITTSBURG BRAKE SHOE COMPANY, OF PITTSBURGH, PENNSYLVANIA, A CORPORATION OF PENNSYLVANIA.

BRAKE-SHOE.

1,219,824.

Specification of Letters Patent. Patented Mar. 20, 1917.

Application filed October 24, 1916. Serial No. 127,364.

To all whom it may concern:

Be it known that I, JOHN JACOB KINZER, a citizen of the United States, and a resident of Wildwood, in the county of Allegheny and State of Pennsylvania, have invented a new and useful Improvement in Brake-Shoes; and I do hereby declare the following to be a full, clear, and exact description thereof.

10 My invention relates to brake-shoes and has special reference to what is known as "filled shoes" by having a composition of metal in the wheel-engaging body, such as is shown and described in my application 15 filed December 30, 1915, Serial No. 69,877.

In this class of brake-shoes it is desired to overcome the difficulties heretofore experienced in forming a brake-shoe, and to form such a shoe which will be cheap, simple 20 and efficient in its form to prevent fracture from expansion and contraction of the same when in use or idle, will have the parts forming its body-engaging portion formed of the same cross-section, and such parts 25 securely held together at all times by the back member or cap. A further object of the invention is to provide a shoe of this character in which the body and back will retain their shape under all conditions, and 30 provide a body which will be formed of a plurality of parts, securely held together at its sides and ends by the body member or cap.

To these ends my invention consists, generally stated, in the novel arrangement, construction and combination of parts, as hereinafter more specifically set forth and described and particularly pointed out in the claims.

40 To enable others skilled in the art to which my invention appertains to construct and use my improved brake-shoe, I will describe the same more fully referring to the accompanying drawing, in which:

45 Figure 1 is a plan or back view of my improved brake-shoe;

Fig. 2 is a side elevation of the same;

Fig. 3 is a cross-section on the line 3—3, Fig. 2, looking in the direction of the arrows;

Fig. 4 is a like view on the line 4—4 Fig. 2, looking in the direction of the arrows; and

Fig. 5 is a view of one of the body sections reversed. 55

Like symbols of reference herein indicate like parts in each of the figures of the drawing.

As illustrated in the drawing A shows my improved brake-shoe, which comprises the supporting back member 1, body or wheel bearing portion 2, and supporting lug 3 through which the brake-shoe is connected in the usual manner to the ordinary approved brake-head or hanger. 60

The body or wheel bearing portion 2 is formed of a series of sectional pieces or blocks 4, preferably of a material such as cast iron or fiber, and the fillers 4' of a composition of frictional material which is 70 well known in the art, thereby forming sections or blocks 4 and 4' of different materials, alternate with each other, and the side faces 5 of such blocks 4, which bear against the fillers 4' are 75 tapering inwardly and outwardly from the back wall or strip 1' of the member 1, for the purposes as hereinafter described. The rear of the sections or blocks 4 and fillers 4' has the supporting back member 1 fitting 80 over the same, which member is formed of metal, preferably steel, and is to be ductile for bending, etc. This back member has the usual short bearing surfaces 7 having recesses 7', which are formed at the ends of 85 the same, and are adapted to abut against bearings on the ends of the brake-shoe or hanger, while the usual central or intermediate bearings on said head or hanger are adapted to abut against such back member 90 on each side of the lug 3. The back member 1 is also provided with a surrounding lip or flange 6, which is bent or turned in from the back wall or strip 1' to form the hollow or receptacle portion 6' in the front of said 95 member and the side and end walls on the same, so that when the sectional body 2 is in place in the receptacle portion 6' on back 1 as hereinafter described, such walls will bear against the end faces 5' on the sections 100

or blocks as well as against the side faces 5" on the end blocks.

The supporting lug 3 can be connected to the shoe A in any suitable manner, and as shown, is formed of metal, such as steel, and is separate from the back wall 1'. The lug 3 is attached to the back wall 1' of the back member 1 by having its supporting legs or standards 3' passed through slots 2' in such back wall, with the ends 3" of such legs bent under said wall, and placed within seats 4" in the blocks 4 and fillers 4'.

In the formation of my improved brake-shoe A, the back member 1 is cut to shape and size desired, after which it is pressed or stamped to give such member the proper curvature for the same and the blocks 4 and 4' for engaging the wheel and to form the back wall 1', the bearing surfaces 7, the surrounding lip or flange 6. The lip 6 in providing for the side and end walls on such back member 1 will be formed outwardly flaring when so pressed or stamped. The back wall 1 is also punched to form the slots 2' in such wall.

The sections or blocks 4 are formed and cut to the shape and size desired, and are placed on such back member 1 and spaced between the side and end walls formed by the lip or flange 6 and within the hollow portion 6' on the back member 1 while such back member is suitably supported to form the tapered spaces or openings 4" between the same by the side faces 5 thereon. The lug 3 having been connected to the back wall 1' in the manner above described, the back 1 and blocks 4 are now supported, in any suitable manner, so that the composition of frictional material can be spread over and between the tapered spaces or openings 4" between the blocks 4, and such material will thereby fill such openings. Suitable pressure can now be applied for packing such material in the openings 4" and to the inner ends of such sections or blocks 4 while such blocks and such ends of the fillers 4' and back member 1 are securely held in dies or any other suitable means, which will bend the flared lip 6 on such back against the end faces 5' on the blocks 4 and 4' and against the side faces 5" on the end blocks 4 and thus form the finished brake-shoe. These blocks 4, and fillers 4' will be held firmly in place in such back member, and between the back wall 1' and lip or flange 6 forming the side and end walls of the member 1 and within the hollow portion 6' formed by said wall 1' and said flange, such side and end walls being drawn securely against the intermediate blocks 4 and 4', end blocks 4 and thus allowing the back member 1 to form a clamping connection with said blocks and fillers.

It will be evident that the filler blocks or

sections can be previously formed to shape 65 and placed between the compressing sections or blocks for being clamped within the back member with such blocks, and said filling material may be plastic, while the material for such filling, blocks and back 70 member can be of any desired kind best suited for the purpose.

Various other modifications and changes in the design and construction of my improved brake-shoe may be resorted to, without departing from the spirit of the invention or sacrificing any of its advantages.

It will also be seen that my improved brake-shoe can be easily and quickly manufactured and assembled for use, while such 80 shoe will also be strong and durable when in use and will be able to withstand knocks or blows of any kind. The shoe will also permit of use until its body is practically worn entirely away, and will have all the 85 substantial advantages of lightness and capability of use on modern high speed trains and especially with steel cars and high brake pressure. The body of the shoe being formed in sections or blocks will also permit 90 of expansion and contraction of the shoe and thereby prevent the same from breaking through heat and cold conditions in the shoe when in use or idle. The shoe being provided with a sectional body member, it 95 will not become warped or twisted out of curvature by frictional heat, but will stay in full contact with the face of the wheel and consequently give a much higher efficiency in retarding heavy and high speed 100 trains, while such sectional body also enables material to be used which will be best suited for the wheel upon which it brakes, and which heretofore has been barred from use by its liability to fracture and other 105 causes.

What I claim as my invention and desire to secure by Letters Patent is:—

1. A brake-shoe comprising a back member and a body member, said body member 110 composed of a plurality of sections or blocks, and side portions on said back member for being bent against said sections or blocks to hold the same in place.

2. A brake-shoe comprising a back member and a body member, said body member composed of a plurality of wedge-shaped sections or blocks, and side portions on said back member for being bent against said sections or blocks to hold the same in place. 115

3. A brake-shoe comprising a back member and a body member composed of a plurality of sections or blocks, and outwardly flared portions on the side of said back-member for being bent against said sections 125 or blocks to hold the same in place.

4. A brake-shoe comprising a back member and a body member composed of a plu-

5 rality of wedge-shaped sections or blocks, and outwardly flared portions on the side of said back-member for being bent against said sections or blocks to hold the same in place.

5. A brake-shoe comprising a back member and a body member, said body member composed of a plurality of sections or blocks, and lip portions on the side of said back member for being bent against said sections or blocks to hold the same in place.

6. A brake-shoe comprising a back-member and a body-member, said body member composed of a plurality of wedge-shaped sections or blocks, and lip portions on the side of said back member for being bent against said sections or blocks to hold the same in place.

7. A brake-shoe comprising a back member and a body member, said body member composed of a plurality of sections or blocks, and outwardly flared portions on the sides and ends of the back member for being bent against said sections or blocks to hold the same in place.

8. A brake-shoe comprising a back member and a body member, said body member composed of a plurality of wedge-shaped sections or blocks, and outwardly flared portions 30 on the sides and ends of the back member for being bent against said sections or blocks to hold the same in place.

35 9. A brake-shoe comprising a back member and a body member, said body member composed of a plurality of sections or blocks, and lip portions on the sides and ends of said back member for being bent against said sections or blocks to hold the same in place.

40 10. A brake-shoe comprising a back member and a body member, said body member composed of a plurality of wedge-shaped sections or blocks, and lip portions on the sides and ends of said back member for being bent against said sections or blocks to hold the same in place.

11. A brake-shoe comprising a back member and a body member, said body member composed of a plurality of sections or blocks, and an outwardly flared flange surrounding the sides and ends of said back member for being bent against said sections or blocks to hold the same in place.

12. A brake-shoe comprising a back member and a body member, said body member composed of a plurality of wedge-shaped sections or blocks, and an outwardly flared flange surrounding the sides and ends of said back member for being bent against said sections or blocks to hold the same in place.

13. A brake-shoe comprising a back member and a body member, said body member composed of a plurality of sections or blocks,

and a flange continuously surrounding the 65 sides and ends of said back member for being bent against said sections or blocks to hold the same in place.

14. A brake-shoe comprising a back member and a body member, said body member composed of a plurality of wedge-shaped sections or blocks, and a flange continuously surrounding the sides and ends of said back member for being bent against said sections or blocks to hold the same in place. 75

15. A brake-shoe comprising a back member and a body member, said body member composed of a plurality of sections or blocks, and an outwardly flared flange continuously surrounding the sides and ends of said back member for being bent against said sections or blocks to hold the same in place. 80

16. A brake-shoe comprising a back member and a body member, said body member composed of a plurality of wedge-shaped sections or blocks, and an outwardly flared flange continuously surrounding the sides and ends of said back member for being bent against said sections or blocks to hold the same in place. 85

17. In a brake-shoe, the combination with the body and wheel bearing portion, of a back member formed of a ductile metal engaging therewith, said member having flange portions thereon for being bent 95 against said body member to hold the parts in place.

18. In a brake-shoe, the combination with the body and wheel bearing portion, of a back member formed of a ductile metal engaging therewith, said member having outwardly flared flange portions thereon for being bent against said body member to hold the parts in place. 100

19. In a brake-shoe, the combination with 105
the body and wheel bearing portion, of a
back member formed of a ductile metal en-
gaging therewith, said member having out-
wardly flared side flange portions thereon
for being bent against said body member to 110
hold the parts in place.

20. In a brake-shoe, the combination with the body and wheel bearing portion, of a back member formed of a ductile metal engaging therewith, said member having outwardly flared end flange portions thereon for being bent against said body member to hold the parts in place. 115

21. In a brake shoe, the combination with the body and wheel bearing portion, of a back member formed of a ductile metal engaging therewith, said member having outwardly flared side and end flange portions thereon for being bent against said body member to hold the parts in place. 120 125

22. In a brake-shoe, the combination with the body and wheel bearing portion, of a back member engaging therewith, said mem-

ber having flange portions thereon for being bent against said body member to hold the parts in place.

23. In a brake-shoe, the combination with the body and wheel bearing portion, of a back member engaging therewith, said member having outwardly flared flange portions thereon for being bent against said body member to hold the parts in place.

10 24. In a brake-shoe, the combination with the body and wheel bearing portion, of a back member engaging therewith, said member having outwardly flared side flange portions thereon for being bent against said body member to hold the parts in place.

15 25. In a brake-shoe, the combination with the body and wheel bearing portion, of a

back member engaging therewith, said member having outwardly flared end flange portions thereon for being bent against said body member to hold the parts in place.

26. In a brake-shoe, the combination with the body and the wheel bearing portion, of a back member engaging therewith, said member having outwardly flared side and 25 end flange portions thereon for being bent against said body member to hold the parts in place.

In testimony whereof I, the said JOHN JACOB KINZER, have hereunto set my hand. 30
JOHN JACOB KINZER.
